UNITED STATES PATENT OFFICE.

ROBERT ANDERSON, OF BROOKS, ALBERTA, CANADA, ASSIGNOR OF ONE-HALF TO
PETER MACGREGOR, OF DETROIT, MICHIGAN.

BOILER.

Application filed April 29, 1921. Serial No. 465,381.

To all whom it may concern:

Be it known that I, ROBERT ANDERSON, a citizen of the Dominion of Canada, and a resident of Brooks, in the Province of Alberta and Dominion of Canada, have invented a new and Improved Boiler, of which the following is a description.

The general object of my invention is to provide an efficient boiler for steam or hot water heating and constructed of few and simple parts so arranged as to facilitate the assemblage, or the disassemblage in order to effect repairs or renewal of parts.

The invention also make provision for a thorough cleaning of vertical tubes employed, and embodies other distinctive features as will clearly appear.

Reference is to be had to the accompanying drawings forming part of this specification, it being understood that the drawings are merely illustrative of one example of the invention.

Figure 1 is a vertical section of a boiler embodying my invention;

25 Figure 2 is a horizontal section on the line 2—2, Figure 1;

Figure 3 is a horizontal section on the line 3—3, Figure 1;

30 Figure 4 is a horizontal section on the line 4—4, Figure 1;

Figure 5 is a horizontal section on the line 5—5, Figure 1;

Figure 6 is a horizontal section on the line 6—6, Figure 1;

35 Figure 7 is a plan view of the scraper;

Figure 8 is a horizontal section on the line 8—8, Figure 1;

Figure 9 is a plan view of the grate.

In carrying out my invention in accordance with the illustrated example I provide supporting means in the form of legs 10 employed in suitable number about the boiler, one of the legs being shown in Figure 1. On and between the legs 10 are supported double doors 11 hinged to the legs as at 11^a, the doors of a pair overlapping as at 11^b, one of the doors of each pair having a handle 11^c. The doors 11 enclose the fire chamber and ashpit. Within the 45 ashpit is a grate structure 12 open at the center and here shown as formed in three sections. Over the open center of the grate is a conical cap 15 to deflect the fuel falling thereon laterally outward onto an annular grate cleaner 14 superposed on the grate sec-

tions 12, and formed with a socket 14^a to receive a shaker. The cleaner may as shown be formed in half sections overlapping at their adjacent edges as indicated at 14^b in Figure 8. The grate sections have support 60 in the illustrated form on a plurality of legs 13, here shown as 3 in number. The grate structure 12 has an annular rim flange 12^a and an inner annular flange 12^b, said flanges being formed in arcuate sections on 65 the respective grate sections. The legs 10 carry at their upper ends a ring 16 on which is an upstanding annular flange 17 within which is received the outer boiler shell 18. On the legs 10 also, at the inner sides, at 70 the top, are flanges 19 directed laterally inward, the inner edges 19^a of said flanges being depressed in curved form and serving to receive and support a lower annular water header 20.

An inner shell 21 is provided with external lugs 22 resting on lugs 20^a of header 20. Below and suspended from the header 20 is an annular mud drum 23 having a plurality of pipes 24 connected therewith, two 80 of said pipes serving in practice as water inlets and the third to be employed as a blow-off. The drum 23 is connected with and suspended from the header 20 by short stay tubes 25 threaded at their ends respectively into the drum and header and provided with upper and lower packing nuts 26, 26^a, the lower nut bearing against the upper ground face of the drum and the upper nut bearing against the internally 91 threaded nipples 27 on the header.

Vertical tubes rise from the header 20 and they are disposed in groups, there being in each group an outer pair of tubes 28 and an inner tube 28^a in staggered relation to 95 the outer tubes, while between the tubes 28, 28^a is a tube 29. The upper ends of each group of tubes 28, 28^a, 29 are connected with one of a plurality of water chambers or individual headers 30. The central tubes 29 are threaded into the lower header 20 and into water chambers 30 and upper and lower packing nuts 31, 31^a are provided on the threaded portions of said tubes. The tubes 28, 28^a are clamped in position between the header 20 and the water chambers 30 through the medium of the tubes 29 so that by turning back the nuts 31, 31^a the tubes 29 may be taken out and this will release the tubes 28, 28^a. 105

Above the annular series of water chambers 30 is an annular steam chamber 32 connected with said chambers 30 by short stay pipes 33 having upper and lower packing nuts 34, 34^a, said pipes being threaded into the steam chamber and water chambers respectively. Lateral pipes 35, 35^a lead from the steam chamber 32 and one of the chambers 30 for connection with a level gage 10 (not shown). Vertical discharge pipes 36 lead from the steam chamber 32 and it will be understood that when the boiler is used in a hot-water heating system the annular chamber 32 will contain water instead of steam. A cap 37 fits over the outer shell 18 and inner shell 21 and has flanges 37^a, 37^b resting respectively on said shells. Said cap 37 presents an open center in register with the inner shell, the opening being 20 closed by a lid 37^c for charging the inner shell with fuel. The interior of the cap 37 is in communication with the annular space between the inner and outer shells so that the hot products may rise in said 25 space and circulate about the tubes 28, 28^a, 29. A smoke pipe 38 rises from the cap 37. In order to scrape the tubes 28, 28^a, 29 effectively and with facility, I provide an annular scraper 39 in the space between the 30 shells through which scraper the tubes extend so that the scraper may slide vertically thereon. The scraper is composed preferably of upper and lower plates perforated for the water tubes and an intermediate plate 39^a. 35 Rods 40 rise vertically from the scrapers and extend through the cap 37, the upper ends of the rods being connected with wires 41 to extend to any suitable point for the convenient raising and lowering of the scraper 40 to remove any deposit from the exterior of the tubes.

I would add that one door 11 of each pair

is offset at the free edge and the offset portion is overlapped at the inner side by the other door of the pair. One of the handles 45 11^c is provided on that door of each pair having the offset edge, and the laterally directed inner end 11^d of the handle overlaps the other door of the pair, whereby the handle serves as a latch for the pair of 50 doors.

I would state in conclusion that while the illustrated example constitutes a practical embodiment of my invention, I do not limit myself strictly to the exact details 55 herein illustrated, since manifestly the same can be considerably varied without departure from the spirit of the invention as defined in the appended claim.

Having thus described my invention, I 60 claim:

A boiler of the class described, including a ring, means supporting said ring, series of doors on said supporting means and enclosing the fire chamber and ash pit of the 65 boiler, an outer shell supported on said ring, an annular lower header supported on said supporting means, and having a water inlet, an annular mud drum suspended by stay pipes from said header and communicating therewith, an inner shell supported on said header, vertical tubes rising from said header between the shells, separate chambers with which separate groups of 70 said vertical tubes communicate at their upper ends, certain of the tubes being threaded into the lower header and into said chambers, others of each group being held clamped between the chambers and lower header through the medium of the threaded tubes, and an annular chamber above and 75 in communication with said separate chambers.

ROBERT ANDERSON.
